UNITED STATES PATENT OFFICE.

ALMIE M. JENNESS, OF DOVER, NEW HAMPSHIRE.

BED ATTACHMENT.

Application filed February 23, 1924. Serial No. 694,735.

To all whom it may concern:

Be it known that I, ALMIE M. JENNESS, a citizen of the United States, residing at Dover, in the county of Strafford and State of New Hampshire, have invented new and useful Improvements in Bed Attachments, of which the following is a specification.

This invention relates to beds and more particularly to a foot rail therefor.

10 The primary object of this invention resides in providing means to be attached to a bed, for preventing a patient therein from sliding toward the foot of the bed.

Another object of this invention resides 15 in the provision of a foot rail for beds capable of being adjusted to fit beds having mattresses of different thicknesses.

A still further object of this invention resides in the provision of a foot rail for 20 beds which is capable of being adjusted to afford comfort to a patient resting his feet thereagainst.

With these and other objects in view, this invention resides in certain novel features 25 of construction, arrangement and combination of elements to be hereinafter more particularly set forth in the specification, illustrated in the accompanying drawings and pointed out in the appended claim, it being understood that the right is reserved to make 30 such departures from the present disclosure as come within the scope of the claim.

In the accompanying drawings forming part of this application:—

35 Fig. 1 is a plane view of a bed showing the elements of this invention in operative position thereon.

Fig. 2 is a side view thereof.

Fig. 3 is a sectional view on line 3—3 of 40 Fig. 2.

Fig. 4 is an enlarged detail vertical sectional view of one of the adjustable columns.

45 Fig. 5 is a detailed perspective view of one of the standards.

Fig. 6 is a detail perspective view of the foot rail.

Fig. 7 is a similar view of one of the adjustable heads of the standards.

In the present illustration of this invention, the B designates a bed to each side rail R of which is rigidly secured by suitable fastening elements an elongated clamp 5, each of which is provided with a projecting tubular standard 6 for the reception of adjustable columns 7 telescopically disposed therein.

The adjustable columns are held in rigid relation with the tubular standards through the instrumentality of set-screws 8 or the like, thus it will be observed that the columns can be regulated to various heights in the standards.

Adjustably secured to the free or outer end of each adjustable column 7 is a slotted 65 head member 9 adapted to accommodate the opposite ends of a foot rail 12 and support it in any desired axial relation to the trunnion of the head.

The opposite ends of the foot rail 12 70 rests in the opposed slots 13 in the head members 9 and is formed so as to dispose a round surface 14 toward the patient to eliminate the possibility of discomfort to the occupant of the bed.

75 In the utilization of the aforesaid elements, the clamps 5 are rigidly secured in the desired position on the rails of a bed, preferably adjacent the foot thereof, with their tubular standards extended adjacent 80 the opposite sides of the mattress of the bed, whereupon the adjustable columns are clamped in rigid relation thereto by suitable fastening elements after the foot rail 12 has been properly disposed on the surface of the mattress.

85 With this invention fully described, it is manifest that an article of comfort is provided for patients confined to beds and, through the simplicity of the assemblage 90 involved, the same can be readily secured to any type of bed and adjusted to meet the prevailing necessities for comfort to a sick patient.

Having thus described my invention, what 95 I desire to protect by Letters Patent is:

An attachment of the character described for beds, comprising clamps having tubular

standards projecting therefrom, opposed columns adjustably supported in the standards, said columns having serrated portions at their free ends, heads projecting from 5 said columns and having serrated portions engaging those of the columns, means for adjusting said heads on said columns, op-

posed depressions in the opposite faces of said heads, and a telescopic foot rail having its ends loosely fitting into the depressions 10 of the said heads.

In testimony whereof I affix my signature.

ALMIE M. JENNESS.
